UNITED STATES PATENT OFFICE.

JAMES D. REIFSNYDER AND HENRY G. SCHWERDTLE, OF PHILADELPHIA, PENNSYLVANIA, ASSIGNEES TO STOKES & SMITH COMPANY, OF SUMMERDALE, PENNSYLVANIA, A CORPORATION OF PENNSYLVANIA.

MACHINE FOR FORMING LONG-FLAP WRAPPED PACKAGES.

1,152,356.

specification of Letters Patent. Patented Aug. 31, 1915.

Application filed June 13, 1914. Serial No. 845,023.

To all whom it may concern:

Be it known that we, JAMES D. REIFSNYDER and HENRY G. SCHWERDTLE, citizens of the United States, residing at Philadelphia, in the State of Pennsylvania, have invented new and useful Improvements in Machines for Forming Long-Flap Wrapped Packages, of which the following is a specification.

10 This invention relates to a machine for placing covers or wrappers on an article such as a box or package. Machines having some of the features of the mechanism described in the following specification have been used for placing wrappers on packages in such a way that the wrapper presents flaps on its upper side which fold over the upper face of the box or package. Heretofore these flaps have been of substantially 15 the same dimensions, and are usually of 20 relatively narrow width.

One of the objects of this invention is to produce a machine which is capable of applying an adhesive wrapper to a box or package when the wrapper has a special 25 form such that the finished wrapped package will present a top flap or flaps on its upper side, substantially covering the upper wall of the box or package; and which may 30 overlie narrow inturned edges of the wrapper such as referred to above.

In some machines of the type referred to the package being wrapped is usually held in such a way that folder members disposed around the position of the package can be moved inwardly to apply the wrapper neatly to the box or package and to fold over the flaps on its upper wall.

One of the objects of the present invention 40 is to provide a very simple arrangement whereby these folder members may be operated, and the relative time of their advance regulated, also to provide a construction which facilitates changing the amount 45 of advance of the folder members.

A further object of the invention is to provide improved means for ejecting the wrapped package from the machine and for controlling the time of operation of this 50 ejector.

Further objects of the invention will appear more fully hereinafter.

In the drawing, which illustrates the pre-

ferred embodiment of our invention, Figure 1 is a side elevation of a machine to which our invention has been applied. Fig. 2 is a vertical cross section through the machine taken in a plane at right angles to the plane of projection in Fig. 1, only the lower part of the machine is shown in section. Fig. 3 is a horizontal section and partial plane broken away. Fig. 4 is a detail upon an enlarged scale showing parts of the mechanism in cross section and in detail. Fig. 5 is a plan showing a form of blank we may use in a machine where there is to be a single long flap extending across the upper face of the wrapped package. Fig. 6 is a side elevation showing the first step of the process of applying the wrapper to the box or package. Fig. 7 shows the next step, consisting substantially in folding in the end laps of the blank. Fig. 8 shows the next operation by the machine, consisting in folding up the flaps which cover the end walls of the package. Fig. 9 is a side elevation illustrating the last operations of the machine, namely folding down the long flap, and pressing the same on a package. Fig. 10 is a perspective illustrating a partially wrapped box covered with a wrapper having the shape of the blank shown in Fig. 5. This view represents a top flap of the wrapper unattached and as though about to be adherently applied to the box.

Referring more particularly to the parts, 85 Fig. 11 represents the frame of a machine which may be of any suitable form, presenting a base plate 12 and a table 13 disposed above the base plate. On opposite sides of the table, as shown in Fig. 2, brackets 13' are supported in substantially horizontal position, said brackets being adjustable inwardly toward the central axis of the machine by reason of a slot 14 in each bracket, 90 and a clamping bolt 15. The part of the frame which supports these brackets is formed with parallel shoulders or adjusting guides 16, which guide the brackets when they are adjusted inwardly or outwardly when the bolts are loosened. The inner ends of these brackets are formed with upwardly extending necks 17, which support inclined brushes 18 above rollers 19 in the usual manner. The object of these 95 brushes is to fold the side flaps of the wrap-

per up against the vertical walls of the package as it descends. At one side of the table there is provided a feed shelf 20 upon which the operator lays a blank 21 indicated by a dotted line, and on this blank is placed the package 22, which is to have the wrapper applied to it. When the plunger 23 of the machine is elevated the operator places the wrapper and package on the platen 24, and as the plunger 23 descends, the operator alines the box properly by means of gage fingers 25 and 26 depending from a bracket 26^a. The fingers 25 and 26 on the plunger extend downwardly on two adjacent walls of the package and hold it in position. The package then passes downwardly between the rollers 19, and as it passes downwardly the brushes 18 fold up and affix the side flaps of the wrapper as indicated most clearly in Fig. 6. The object of the adjustment which is possible by reason of the slots 14^a is to enable the distance between rollers 19 to be adjusted to suit packages of different width.

25 A very simple form of the blank is shown in Fig. 5, said blank comprising a body portion 27, side flaps 28, end flaps 29, the side flaps 28 having end laps 30, and one of the side flaps 28 being provided with a single long top flap 31, which is to form the top flap of the wrapper on the finished package. As the plunger 23 forces the package down between the rollers 19, the rollers press the flaps 28 closely against and cause them to adhere to the long sides of the box or package. The platen 24 is provided with a stem 32, and has a spring 33 tending to hold the platen up when the plunger descends, and offering a slight resistance to the descent of the plunger. After the plunger has passed the rollers 19, the end laps 30 are folded around the vertical corners of the box by means of end-turn-in wings 34 of usual construction, the same being preferably mounted on vertical pivot pins 35 in brackets 36, said brackets being mounted on oppositely disposed horizontal bars 37 arranged in pairs so that each bar 37 controls the advance and withdrawal of two of the devices 34. The brackets 36 are provided with rigid guide stems 38 which may be guided in any suitable manner, such as by means of guide lugs 39 on the brackets 13^a.

55 The operation of the end-trun-in wings is illustrated in Fig. 7. After these devices have operated they withdraw and the box then passes downwardly between end folding brushes 40, which fold up and adhesively apply the end flaps 29 of the wrapper as illustrated most clearly in Fig. 8. The plunger 23 then forces the package farther downwardly to enable the unaffixed remainder of the wrapper to be affixed to the remaining uncovered wall, in this instance the

upper wall of the box or package. In order to enable these flaps to be turned in over the upper faces of the package it is necessary to provide for the withdrawal of the plunger 23. This is accomplished by means of a cam slot 41 in a cam 42, which engages a roller 43 on the side of the plunger 23. The end brushes 40 are preferably mounted on adjustable brackets 40^a on the table 13.

70 The withdrawal of the plunger 23 is illustrated in Fig. 9. In order to prevent the platen 24 from following the plunger up on this withdrawal movement, machines of this type are provided with means for clamping the stem 32 of the platen. We prefer to employ a clamp 44 comprising two opposite jaws 45 connected by a pivot pin 46, the said jaws being operated by toggle levers 47 connected with a stem 48 extending substantially radially from the central vertical axis of the machine, see Fig. 3. The outer end of the stem 48 has a roller 48^a rolling on a cam 48^b, and this cam is carried rigidly on a vertical shaft 48^c. The cam has an operating face 48^d which is so placed that the stem will move inwardly and operate the clamp to hold the platen down at the moment of the temporary withdrawal of the plunger 23.

75 Referring again to the blank shown in Fig. 5, it will be seen that the end flaps 28 and 29 have short edge flaps 28^a and 29^a, and these short edge flaps will be folded over the upper face of the box as indicated in Fig. 10, and the long flap 31 is then to be folded 100 over upon the same. The mechanism for this purpose is arranged particularly with a view to enabling the time of the operation of the folder members, which fold the flaps, to be regulated in relation to each other, and 105 the construction is also intended to facilitate giving the folder which folds over the top flap a movement sufficient to accomplish its purpose effectively. In the form of blank shown in Fig. 5, which is shown merely by 110 way of illustration, there are three narrow top flaps and one long flap. The movements of the parts which apply these flaps should be sufficient to press the entire area of the flap down onto the upper wall of the box so as to adherently apply the flaps thereto. If one or more of the flaps should be long, the member which applies it should have a longer stroke. In the present instance there is a single long flap, and the member 79 which adherently applies it to the box preferably moves completely across the upper face of the box and presses the flap throughout its entire area down upon the box. The preferred mechanism for this purpose will 115 now be described. On three sides of the machine we provide presser blocks 49, and these presser blocks are preferably attached on bars 50, said bars having guide stems 51 attached to the ends thereof and guided in 120

suitable lugs 52 on the sides of the brackets 13', shown most clearly in Fig. 3. These blocks 49 preferably have resilient pads 53 on their faces which press against opposite sides of the box and hold the same in position while the folder members are operating to fold-over and adherently attach the flaps. The folder members for a box having a wrapper of this form, preferably comprise three members which are substantially alike in construction and mode of operation for folding in the three short flaps 28^a and 29^a. The folder members for the short flaps preferably consist of elongated plates 55, the ends of which are bent downwardly so as to form fingers 55^a for engaging the flaps, and these plates are mounted so as to move inwardly a short distance so as to fold over the short flaps. The mode of operation of these plates is indicated at the left of Fig. 9. Each of these plates is preferably mounted on a bar 56, the ends of which are provided with stems 57 which may be similar to stems 51, and which are guided in a similar manner in the aforesaid guide lugs 52.

The arrangement for advancing the presser blocks and the edge-tuck-in fingers for the sides of the box which correspond to the short edge flaps 28^a and 29^a will now be described. This mechanism is most clearly illustrated at the left of Fig. 3, and at the left of Fig. 2. In order to actuate the presser blocks 49 the presser block is preferably provided with an actuating stem 58 which is preferably centrally disposed on the bar 50 pivotally attached to the same. This stem 58 extends outwardly horizontally between the two guide stems 51 and its outer end has attached rigidly thereto the bracket 59, the lower portion of which is formed into a yoke 60, which engages neatly over the actuating shaft 61 on this side of the machine. This shaft 61 is provided with an actuator for actuating the presser block preferably in the form of a cam 62, which shoves the bracket 59 forwardly by engaging a roller 63 on the side of the bracket. The bracket 59 is preferably attached to the stem 58 by means of a set screw 64, which arrangement enables the position of the stem to be adjusted in or out on the bracket so as to adjust the position of the presser block with relation to the wall of the package. A similar arrangement is adopted with respect to the edge-tuck-in fingers 55^a, that is the bars 56 corresponding to these fingers 55^a are provided each with a stem 65, centrally disposed on the bar and attached to the bar pivotally, and the rear end of this stem is attached to an adjustable bracket 66 similar to the bracket 59, and similarly formed with a yoke engaging the shaft 61, a set screw 67 enabling the position of the stem to be adjusted to adjust the tuck-in

finger toward or away from the central axis of the machine. On the stems 51 and 57 helical springs 68 are provided, which tend to return the presser blocks and the tuck-in fingers and hold their rollers 63 and 69 against their corresponding cams 62 and 70.

In order to move in and out the end-turn-in wings 34 we provide the shaft 61 with a cam 71, see Fig. 3, which operates a lever 72, rigid with the arm 72^a which is connected by a link 73 to a sleeve 74 on the rear end of one of the guide stems 38, and this sleeve 74 is attached by means of a set screw 75 which enables the position of the stem 38 to be adjusted as desired. With this arrangement evidently as the shaft 61 rotates, the end-tuck-in fingers 34 will be moved inwardly and then withdrawn. The use of cams in this way which are unattached to the parts which they actuate is advantageous, as it enables cams of different shape to be substituted for each other when desired; this greatly facilitates making changes in the amount of stroke of the different parts, and it also facilitates the nice adjustment of the time relation of operation of these parts. For this purpose, the cams are all preferably attached to the shaft 61 by means of set screws, such as the set screws 76, Fig. 3. It should be understood that in the present embodiment this mechanism for folding in the three short flaps 28^a, 29^a, is duplicated at the three points 77, 78 and 79, Fig. 3, that is on three sides of the machine. On the fourth side 78' which corresponds to the position of a long flap 31, it is desirable to give the edge-tuck-in finger 79' for the long flap a different form and a longer stroke. The preferred form of this finger is illustrated in Fig. 9. It consists of a slightly offset plate the outer edge of which is attached to a bar 80, said bar having horizontal guide stems 81 attached near the ends thereof and guided to slide horizontally in lugs 82 on the corresponding bracket 13'. Near the middle of the bar 80 there is attached pivotally an actuating stem 83, and this actuating stem extends rearwardly and carries an adjustable sleeve 84 which is attached to the stem 83 between adjustable collars 85 by means of set screws 86. In order to give this stem 83 an increased movement we prefer to employ the construction shown at the right in Fig. 2, and partly shown in an enlarged scale in Fig. 4. For this purpose we prefer to provide a bracket 87 on the base plate 12, the upper end of which bracket supports the lever 88, the upper end of which is rocked by a cam slot 89 in a cam 90, said cam being attached on a shaft 91 parallel with the shaft 61 on the opposite side of the machine. At a depressed point in the bracket 87 there is pivotally mounted a bell crank lever 92 the upper arm 93 of which is connected by a pin and slot connec-

- tion 94 with the aforesaid sleeve 84, the arrangement being such that when the arm 93 rocks forward and back, it will reciprocate the stem 83 and the tuck-in finger actuated thereby. The bell crank lever 92 is preferably actuated by a link 95 from the lower end of the lever 88, said link being adjustably connected to the bell crank arm 93 by means of a slot 96 and clamping pin 97.
- 10 The upper end of the arm 93 of the bell crank lever is preferably bent slightly rearwardly as indicated. The bell crank lever 92 has its lower arm 98 attached to a spring 99 anchored at 100 on the frame, and this 15 spring assists in returning the tuck-in finger after it has had a forward movement. Evidently by raising or lowering the pivot pin 97 in the slot 96 the amount of stroke of the tuck-in finger may be regulated. For instance if pin 97 is placed higher up in the 20 slot the tuck-in finger will have a shorter stroke and vice versa. On this side of the machine a presser block 101 is provided similar to the presser blocks 49 already described, 25 and this presser block 101 is preferably guided in the same way and actuated in the same way as the presser blocks 49, already described. The cam 102 for this purpose is on shaft 91 as indicated in Fig. 1, and actuates a bracket 103 attached on actuating stem 104 attached to a bar 105 carrying presser block 101. The bar 105 is guided by means of guide stems 106 sliding in lugs 107 on the corresponding bracket 13' (Fig. 1).
- 30 The shafts 108, 91, 110 and 61 are preferably connected together in series by bevel gears, and the vertical ejector shaft 48° drives shaft 108 so that all these shafts rotate in unison. For this purpose the ejector 35 shaft 48° is arranged to drive the shaft 91 through a horizontal shaft 108 and bevel gears 109, and the shaft 91 is arranged to drive the shaft 61 through a shaft 110 which carries the cams 111 and 112 for operating their corresponding folder members. The 40 shaft 110 is driven through suitable bevel gears 113, and similar bevel gears 114 are provided for driving the shaft 61. The shafts 108, 91, 110 and 61 are preferably disposed around the sides of a rectangle (see Fig. 3.). While this is the preferred arrangement for driving the shafts it is understood that any suitable arrangement may be adopted which will insure that the shafts 45 rotate in unison, that is the same angular movement of one shaft corresponds to the same angular movement of another shaft. While we prefer to use shafts for this purpose it is understood that this is the preferred form of the rotatable members which 50 operate the folder members. By actuating the folder members from parts rotating in unison in this way, it is evident that a very nice adjustment can be effected in the regulation of the time of operation of the dif-
- ferent folder members. This facility is augmented by the feature of the cams, the angular position of which can be adjusted when desired on the corresponding shafts. After the long flap end-tuck-in finger 79' has 55 moved forwardly and substantially across the upper face of the package it withdraws and then the plunger 23 comes down on the package and presses the long flap down upon the same. The plunger then withdraws and the package is ejected from the machine by an ejector device 115. This ejector device preferably comprises a guide 116 which may be part of the upper frame 117 which supports the lever 23 which operates the plunger 23. The ejector device also preferably comprises a horizontal stem 118 mounted to slide horizontally in the guide 116, the inner end of the stem projecting over to a point near the platen and provided with a head 119 which is adapted to strike the package, and throw it off of the platen. The ejector stem 118 is preferably actuated in its forward movement by a coil spring 120, which is arranged between the 60 back end of the guide and an adjustable collar 121 on the stem. Just forward of the collar 121 the stem is provided with a sleeve 122 having a pin and slot connection 123 with an arm of a bell crank lever 124, said bell crank lever being mounted on a vertical stud 125, and having a short arm 126 carrying a roller 129 running on the face of an ejector cam or disk 127, said cam being rigidly secured on the ejector shaft 51. At 65 the proper point in its periphery this cam is provided with a deep notch or gap 128. When the parts are in the position shown in Fig. 3. the cam or disk 127 holds the spring 120 compressed, and holds back the 70 stem 118, but when the notch 128 comes under the roller 129 the spring 120 is released and suddenly drives the ejector stem forwardly so as to push the package off of the platen. In this connection it is understood that after the plunger has moved 75 down upon the long flap 31 and compressed the same against the package it withdraws, and as it withdraws the aforesaid cam 50 releases the clamp 45 so as to enable the 80 platen to be returned upwardly by its spring 33. The mechanism of the machine is most conveniently driven by means of a worm 130 on a driving shaft 131, carrying belt pulleys 132. This worm 130 may mesh with 85 a worm wheel 133 on the ejector shaft 48° to drive the mechanism. The rear end of the stem 118 has an adjustable head 135, and on the outside of the guide 116 a dash pot 136 is provided which receives the head 135 and cushions the end of the stroke of the ejector. Instead of employing plates such as the plates 55 and 79 as folder members, we may use brushes with vertically disposed bristles which wipe across the upper 90

face of the package to fold over the flaps. These brushes may be employed where the necessity for nice adjustment of the folders to the package is not feasible, or where there is great variation in the depth of the packages.

It is understood that the embodiment of the invention described above is only one of the many embodiments the invention may 10 take, and we do not wish to be limited in the practice of the invention nor of our claims to the particular embodiment set forth.

What we claim is:—

15 1. A machine for applying adhesive wrappers to packages, comprising, in combination, means for folding an adhesive wrapper about a package so as to present a plurality of projecting flaps including a top flap adjacent to an uncovered wall of the package, a plurality of movable members for adherently applying to the package all of said flaps except the said top flap, a member for adherently applying the said top flap, and means for moving said last member across the said uncovered wall to apply the said top flap adhesively thereto.

20 2. A machine for applying adhesive wrappers to packages, comprising, in combination, means for folding an adhesive wrapper about a package so as to present a plurality of projecting flaps including a top flap adjacent to an uncovered wall of the package, a plurality of movable members for adherently applying the flaps of the adhesive wrapper to the package, means for actuating the same to adherently apply to the package all of said flaps except the said top flap, a member for adherently applying to the package the said top flap, and means for moving said last member substantially across the said uncovered wall after the other flaps have been folded, to adherently apply the said long flap thereto.

25 3. A machine for applying adhesive wrappers to packages, comprising, in combination, means for folding an adhesive wrapper about a package so as to present a plurality of projecting flaps including a top flap adjacent to an uncovered wall of the package, a plurality of movable members for adherently applying to the package all of said flaps except the top flap, a member for adherently applying the said top flap to the package, a cam for actuating the same and a lever actuated by said cam and imparting movement to said last named member to press and adherently apply the entire area of said top flap against said uncovered wall.

30 4. A machine for applying adhesive wrappers to packages, comprising, in combination, a plurality of oppositely disposed tuck-in-fingers, means for partially wrapping a package and for holding the partially

wrapped package in the space between said fingers, means for guiding said fingers across an adjacent wall of the package to adherently apply part of the wrapper to the package, and means for moving one of said fingers substantially completely across the said adjacent wall to press and adherently apply a flap of the wrapper to the said adjacent wall.

35 5. In a machine of the class described, an ejector for removing the finished article, comprising a plunger, a spring tending to advance said plunger to eject the article, a bell-crank lever having an arm for engaging said plunger to hold the same in a retracted position, and a rotatable cam rotating with the mechanism of the machine normally holding said lever in a position to maintain said plunger retracted, and having a deep notch for releasing said lever to permit said spring to advance the plunger, said bell crank lever having a second arm with a roller adapted to move into said notch and permit said plunger to be advanced by said spring.

40 6. In a machine for placing a wrapper on a package, in combination, a frame, a plurality of folder members guided on said frame, a plurality of shafts corresponding to said members arranged on the sides of a rectangle and connected in series to rotate in unison, means actuated by said shafts respectively to move said folder members, an ejector shaft arranged to rotate one of said shafts to drive all of said shafts in unison with said ejector shaft, and ejector mechanism controlled by said ejector shaft for ejecting the finished article.

45 7. In a machine for placing a wrapper on a package in combination, a frame, a depressible platen for the package, a plurality of folder members, a plurality of shafts corresponding respectively to said members and arranged to rotate in unison, means actuated by said shafts for moving said folder members respectively, a plunger co-operating with said platen to press the wrapper on the package and to press the package and platen, an ejector shaft, a clamp controlled by said ejector shaft for temporarily holding the said platen depressed, and ejector mechanism controlled by said ejector shaft for ejecting the wrapped package.

50 8. A machine for forming a sealed wrapped package by applying a one-piece adhesively coated wrapper to all the exterior walls thereof, comprising, in combination, means for supporting the package, wrapper applying instrumentalities for adherently applying and affixing the wrapper to all the walls of the package except one uncovered wall so that the wrapper presents an unattached remainder, means for effecting a relative movement between the supporting means and the said applying in-

strumentalities, and means operating after the operation of the said instrumentalities for adherently affixing the remainder of the wrapper to completely cover the remaining 5 uncovered wall and thereby effect the complete covering of the package.

In testimony whereof we have hereunto

set our hands in presence of two subscribing witnesses.
